UNITED STATES PATENT OFFICE.

ALFRED L. DAY, OF CHICAGO, ILLINOIS, ASSIGNOR TO AMERICAN PERFORATOR COMPANY, OF CHICAGO, ILLINOIS, A CORPORATION OF ILLINOIS.

PERFORATING-MACHINE.

1,124,305.

Specification of Letters Patent.

Patented Jan. 12, 1915.

Application filed January 21, 1913. Serial No. 743,266.

To all whom it may concern:

Be it known that I, ALFRED L. DAY, a citizen of the United States, residing at Chicago, in the county of Cook and State of Illinois, have invented new and useful Improvements in Perforating-Machines, of which the following is a full, clear, concise, and exact description, reference being had to the accompanying drawing, forming a part 10 of this specification.

This invention relates to improvements in perforating machines, the object being to improve the wearing qualities of the machine and to simplify and cheapen the construction.

One embodiment of the invention is illustrated in the accompanying drawings and it will be obvious that the improvements may be applied to various forms, sizes and types 20 of machines and that they may differ in structural respects, all within the scope of the appended claims.

In these drawings Figure 1 is a side elevation of a simple hand machine, parts being broken away to show more clearly the features of improvement; Fig. 2 is a cross-sectional view, the plane of section being indicated by the line 2-2 of Fig. 1; Fig. 3 is a perspective detail view of the fixed 30 mandrel on the movable head of the machine; and Fig. 4 is a similar view of one of the rotatable matrix rings.

This machine in general is of the type used for perforating numbers, letters, words 35 or other data, through one or more sheets of paper, as, for example, checks. It includes a plurality of groups of small punches, some of which punches in each group are depressed when the machine is operated to perforate the desired letter, figure or character. In order to select the proper punches in each group for such perforations, the operating head of the machine is provided with a matrix ring or 45 plate for each group of punches, at least for any group in which it is desired to change the character of perforation made by it. The ring is provided at different points with groups of holes adapted when any such 50 point is brought opposite the ends of the punches and the head depressed or moved toward the group to receive the ends of the

non-perforating punches. The remainder of the punches of the group are pressed forward by the solid portion of the ring or 55 plate and serve to perforate the desired character in the sheet.

The present invention relates to improvements in such machines whereby the head or punch operating means may be made 60 much more cheaply and expeditiously than heretofore and the wearing and lasting qualities of the same be much improved.

Referring to the particular machine of the drawings, the base portions 10 and 11 of 65 suitable form and material are bolted or otherwise fastened together to form a rigid member, the two parts being slightly separated at their forward ends to form a slot or mouth to permit the insertion of a sheet or 70 sheets to be perforated. A suitable die plate is carried in the lower portion 10 to cooperate with the punches 12 in making the perforations. The adjacent part of the upper member 11 is provided with a suitable guide 75 plate for the lower ends of the punches, and a plate 13 secured to the upper side edges of this same part forms a guide for the upper end of the punches.

The upper portion of the machine consists of a suitable hollow arm 14, usually of 80 cast metal, pivoted at its rear end to the base portion 11, and carrying the operating head at its forward end. To the cross-member 15 near the forward end of this 85 arm and between its two side members 16 and 17 is secured a suitable mandrel 18 by means of the screw bolt 19. This mandrel is cylindrical in form and carries the rotatable matrix rings 20. A front plate 21 having an annular shoulder to fit within the side members 16 and 17 is secured by screws 22 to the forward ends of the said members 16 and 17 and serves to inclose the forward 90 end of the head.

A lifting plate 23 for the punches is carried by the head between a ledge formed on the inside lower edge of the extension of the front plate 22 and a suitable slot or groove in the corresponding extension of the cross 100 member 15. Said lifting plate is adapted to reciprocate vertically between the side members of the portion 11 of the base and when raised to engage suitable shoulders on

the punches 12. When the head is depressed this plate permits the punches to be depressed also.

A suitable hand lever 30 is pivoted to the upper ends of a link 31, which in turn is pivoted to the portion 11 of the base. This lever has a projection 32 engaging the upper end of a coiled spring 33, which rests at its lower end upon the upper side of the base portion 10. The lever is operated to depress the head and when released both lever and head are raised by the spring.

The rings 20 are sections of comparatively thin tubing, preferably steel, and of such size as to nicely fit over the cylindrical mandrel 18. There should be sufficient clearance to enable them to be easily rotated thereon. These rings 20 are provided at various points about their circumference with suitable apertures arranged to permit the upper ends of certain of the punches to pass therethrough when the head is depressed and not to cause them to perforate the sheet of paper. The other punches of the same group engage the solid or unperforated portions of the ring and are thereby depressed to cause them to perforate the desired character.

The mandrel 18 is provided with a longitudinal groove 34 immediately above the ends of the punches so that there will be sufficient clearance space for their upper ends after they pass through the ring 20. In the upper side of the mandrel 18 is a groove 35 into which a pin 36 for each ring is inserted when the ring is brought to the desired position with the proper matrix over the punch group.

The rings may be provided in any desired number; four are shown in the present instance. Any desired matrix may be made in such rings. The groups of punches may vary in number and size. The rings may be turned by hand or automatically and any desired number of matrices within practicable limits may be placed in the rings. The machine may be operated by hand or power. With a different form of mandrel or supporting back, the matrix plate may differ, and separate plates, flat or otherwise, for each matrix may be employed. In short, the invention as defined by the claims is not confined in its application to the particular form of machine shown nor to one operating in the same way.

By placing suitable markings adjacent the holes in the rings through which the pins 36 pass, the operator can tell what pattern is above the punches of that ring and can set the rings accordingly. The patterns may conveniently be so disposed in the rings that the turning of the ring by the pin 36 until the pin strikes the upper edge of the side member 17 brings the next hole in the ring in line with the groove 35, into which

the pin may then be inserted to hold the ring in proper position. Or the rings may be turned by the fingers to the desired position. A suitable shield 37 of sheet metal may be secured to the head to entirely cover the opening in the front end of the base portion.

By making the mandrel or supporting back of enlarged diameter and grooving it for the punch ends and making the rings or pattern plate of thin material, the cost of the raw materials is greatly reduced since stock materials may be used; the cost of labor is likewise greatly reduced, since the only machining required is the simple operations of making the grooves in the mandrel and drilling the holes on the thin rings, and a longer wearing device is produced since steel may be employed for the rings in place of softer metals. By the use of the thin matrix material together with a suitable backing or support, the invention adapts itself to fields of use not heretofore contemplated for perforating machines, particularly where a plurality of papers or documents are to be marked for each of a list of names or other identifying indicia, as each such name or indicia may be represented by a thin matrix plate or ring which is temporarily placed in the machine for use and then removed to make way for another.

Having thus described my invention what I claim as new and desire to secure by Letters Patent is:

1. In a perforating machine, the combination with a base, of a plurality of punches supported on said base, a movable head, a plurality of comparatively thin matrix plates carried by and movable with said head for causing said punches to operate, and means permitting the removal of any of said matrix plates from said head and the substitution of others therefor.

2. In a perforating machine, a group of punches, and an operating head therefor, said head including a comparatively thin matrix ring having perforations to receive the non-perforating punches of the group, and a supporting mandrel for said ring, said mandrel having a space to receive the ends of the punches that extend through said thin matrix plate during the perforating operation.

3. In a perforating machine, a plurality of groups of punches, and an operating head therefor, said head comprising a fixed cylindrical mandrel relatively movable toward and away from the ends of said groups of punches, a plurality of matrix rings carried on said mandrel, one for each group of punches, and rotatable on said mandrel, each of said rings having a plurality of groups of openings corresponding to the non-perforating punches of each character to be perforated, and said mandrel having a

groove formed therein opposite said groups of punches to receive the ends of said non-perforating punches when they project through the matrix rings in the perforating

5 operation.

4. In a perforating machine, the combination with a plurality of groups of punches, of a mandrel, a plurality of matrix rings on the mandrel, one for each group of 10 punches, and groups of apertures in the rings to accommodate the non-perforating punches of each group.

5. In a perforating machine, the combination with a base, of a plurality of punches 15 supported on said base, a movable head, a plurality of comparatively thin matrix plates carried side by side on said head and

movable therewith, said plates being movable relative to said head and having means whereby they cause the depression of a pre-determined number of said punches according to their position on said head, and means permitting the removal of any of said matrix plates from said head and the substitution of others therefor for causing a different operation of said punches. 20 25

In witness whereof, I have hereunto subscribed my name in the presence of two witnesses.

ALFRED L. DAY.
